Inventor
Archibald Lassell Hale Monro

BY Richard J. ATTORNEY'S

UNITED STATES PATENT OFFICE.

ARCHIBALD VASSEL HALE MONRO, OF DUNEDIN, NEW ZEALAND.

TACKLE-BLOCK.

SPECIFICATION forming part of Letters Patent No. 780,520, dated January 24, 1905.

Application filed May 24, 1904. Serial No. 209,531.

To all whom it may concern:

Be it known that I, ARCHIBALD VASSEL HALE MONRO, master mariner, of Dunedin, New Zealand, have invented certain new and useful 5 Improvements in Tackle-Blocks, of which the following is a specification.

This invention relates to a new and useful improvement in tackle-blocks, and although applicable to any form of blocks where ropes 10 are used it is specially applicable in connection with the raising and lowering of ship's boats from the davits, as hereinafter described.

The object of this invention is to minimize the great difficulty, labor, and risk which are 15 attendant on a boat being hoisted by reason of the necessity of passing the fall of the rope into the thumb-cleat on the davit and making it fast to the belaying-pin attached to the davit in order to cause the fall to lie in a curve down 20 the davit and out of the way of the boat.

I am aware of blocks in which wedge-pieces, a lever, a pull-rope, and a weight at the end of the lever are used; but in these cases the object is to keep the wedge-pieces normally 25 clamped on the rope to be freed by the pull-rope operating the lever, whereas this block has the wedge-pieces normally clear of the ropes and is much simpler, being workable by any one and according to the ordinary prac- 30 tice of seamen, and is particularly superior when lowering away a boat on a dark night.

The invention consists of the features and combination and arrangement of parts hereinafter described with reference to the accompanying drawings and particularly pointed out 35 in the claims.

In the drawings, Figure 1 is a side view of a bracket with a portion of one of the cheeks cut away, showing gripper-pieces in position. 40 Fig. 2 is a sectional view through Fig. 1. Fig. 3 shows the invention applied to a davit for boat raising and lowering with a rope holding the wedges jammed.

Pulleys 1, 2, and 3 are supported by the bearing-cheeks 4, 5, 6, and 7 in the usual manner for lifting-tackle. The cheeks are provided with upward extensions 8, 9, 10, and 11 for the purpose of supporting the gripper-pieces 12, 45 13, and 14, which are for the purpose of jam-

ming the ropes 15 to the pulleys, as hereinafter 50 described. The gripper-pieces are provided with smooth curved ends 16 for the purpose of preventing any chafe or cutting of the rope no matter how often the rope is brought in contact with them, the curve being such that the 55 motion of the rope tends to tighten the grip. They are mounted, keyed, or otherwise secured to a spindle 17, adapted to turn freely in its bearings on the bearing-cheeks. A square end 18 of the spindle 17 is fitted to a 60 square hole on a lever 19. A weight 20 at the end of the lever 19 keeps the gripper-pieces normally tilted up, allowing the ropes 15 to run freely over the pulleys when required. A lever-rope 22 is attached to an 65 end 23 of the lever 19, so that when the rope 22 is pulled the grippers immediately jam the rope 15 against the pulleys. This lever-rope is made fast to the deck, so that it cannot foul, such as by the bight being blown into the 70 block.

In operation in raising a boat the rope running round the sheaves is pulled on until the necessary height is gained. The lever-rope 22 is then pulled, causing the grippers 12 13 75 14 to hold the sheave-rope 15, the fall of which can then be easily secured round a thumb-cleat 25 and fastened to a belaying-pin 26, whereupon the lever-rope is released, also releasing the grippers. Should the 80 sheave-rope 15 slip, as on the warping-barrels of a winch 27, or become suddenly detached, a slight jerk on the lever-rope will immediately check the boat from falling and will hold it until released. The object of 85 passing the fall of the rope 15 over the belaying-pin 26 and securing it to the cleat 25 is to insure the boat clearing the rope 15 when being pushed outboard and inboard.

Having now described my invention, what 90 I claim as new, and desire to secure by Letters Patent, is—

1. In a tackle-block such as described the combination therewith of a lever having a weight at one end and wedge-pieces pivoted 95 midway of the lever which are held normally clear of the pulley-ropes and are caused to jam the ropes on the free end of the lever be-

ing pulled substantially as and for the purposes set forth.

2. In a tackle-block such as described the combination therewith of a lever, a pivotal connection midway thereof with the tackle-block, wedge-pieces secured to the pivot, and a weight at one end of said lever whereby the wedge-pieces are normally kept clear of the

ropes running in the block substantially as and for the purposes set forth.

In witness whereof I have hereunto set my hand in presence of two witnesses.

ARCHIBALD VASSEL HALE MONRO.
